US00D416086S

United States Patent [19]

Parris et al.

[11] Patent Number: Des. 416,086

[45] Date of Patent: ** Nov. 2, 1999

[54] **BLUNT CANNULA SPIKE ADAPTER**

[75] Inventors: **Wayne M. Parris**, Anaheim; **William A. Sperko**, Yorba Linda; **Peter N. Cassimatis**, San Clemente; **Martin V. Shabaz**, Santa Ana, all of Calif.

[73] Assignee: **B. Braun Medical, Inc.**, Irvine, Calif.

[**] Term: 14 Years

[21] Appl. No.: 29/077,709

[22] Filed: Oct. 9, 1997

[51] LOC (6) Cl. 24-02

[52] U.S. Cl. D24/112; D24/130

[58] Field of Search D24/112, 130, D24/146, 147; 604/164, 165, 177, 158, 166, 170, 198, 263, 900, 102, 553

[57] **CLAIM**

The ornamental design for a blunt cannula spike adapter, as shown and described.

DESCRIPTION

FIG. 1 is a side perspective view of a blunt cannula spike adapter showing our new design;

FIG. 2 is a top plan view thereof, the bottom plan view being identical thereto;

FIG. 3 is a right side elevational view thereof; FIG. 4 is a left side elevational view thereof; FIG. 5 is a rear elevational view thereof; FIG. 6 is a front elevational view thereof; FIG. 7 is a side perspective view of a second embodiment of a blunt cannula spike adapter showing our new design; FIG. 8 is a top plan view thereof, the bottom plan view being identical thereto; FIG. 9 is a right side elevational view thereof; FIG. 10 is a left side elevational view thereof; FIG. 11 is a rear elevational view thereof; FIG. 12 is a front elevational view thereof; FIG. 13 is a side perspective view of the blunt cannula spike adapter as seen in FIG. 1, with the spike sheath removed; FIG. 14 is a top plan view thereof, the bottom plan view being identical thereto; FIG. 15 is a right side elevational view thereof; FIG. 16 is a left side elevational view thereof; FIG. 17 is a rear elevational view thereof; FIG. 18 is a front elevational view thereof; FIG. 19 is a side perspective view of the second embodiment as seen in FIG. 7, with the spike sheath removed; FIG. 20 is a top plan view thereof, the bottom plan view being identical thereto; FIG. 21 is a right side elevational view thereof; FIG. 22 is a left side elevational view thereof; FIG. 23 is a rear elevational view thereof; FIG. 24 is a front elevational view thereof; FIG. 25 is a side perspective view of the blunt cannula spike adapter as seen in FIG. 1, with the spike sheath and blunt cannula removed; FIG. 26 is a top plan view thereof, the bottom plan view being identical thereto; FIG. 27 is a right side elevational view thereof; FIG. 28 is a left side elevational view thereof; FIG. 29 is a rear elevational view thereof; FIG. 30 is a front elevational view thereof; FIG. 31 is a side perspective view of the second embodiment as seen in FIG. 7, with the spike sheath and blunt cannula removed; FIG. 32 is a top plan view thereof, the bottom plan view being identical thereto; FIG. 33 is a right side elevational view thereof; FIG. 34 is a left side elevational view thereof; FIG. 35 is a rear elevational view thereof; and, FIG. 36 is a front elevational view thereof.
